CLAIM

(52) **U.S. Cl.** D14/258

The ornamental design for a combined digital disc player and automotive navigation system, as shown and described.

(58) **Field of Classification Search** D10/65,

DESCRIPTION

D10/80; D12/192; D14/496, 157, 257–258,

FIG. 1 is a perspective view of a combined digital disc player and automotive navigation system showing my new design;

D14/299, 217, 126, 132; 455/344–351; 369/75.11,

FIG. 2 is a perspective view showing the monitor (the navigation device) detaching thereof;

369/75.21, 77.11, 77.21; 720/612, 619, 647,

FIG. 3 is a front view of FIG. 1;

720/655

FIG. 4 is a left side view thereof;

See application file for complete search history.

FIG. 5 is a right side view thereof;

FIG. 6 is a top plan view thereof;

FIG. 7 is a bottom plan view thereof; and,

(56) **References Cited**

FIG. 8 is a perspective view showing the front panel opening thereof.

U.S. PATENT DOCUMENTS

The broken line shown in FIGS. 1 to 8 is for illustrative purposes only and forms no part of the claimed design.
